UNITED STATES PATENT OFFICE.

JOSEPH MASON AND HENRY MASON, OF NEW YORK, N. Y.

SAFETY-BURNER.

SPECIFICATION forming part of Letters Patent No. 402,262, dated April 30, 1889.

Application filed November 24, 1888. Serial No. 291,765. (No model.)

To all whom it may concern:

Be it known that we, JOSEPH MASON and HENRY MASON, both of the city, county, and State of New York, have invented a new and 5 Improved Safety-Burner, of which the following is a full, clear, and exact description.

This invention relates to gas-burners, the object of the invention being to provide for the automatic shutting off of the gas-supply 10 should the gas accidentally go out or be blown out by persons ignorant of the operation of the ordinary gas-fixture, whereby all danger of explosion or the asphyxiation of those in the apartment where the safety-burner is will 15 be avoided.

To the end above named the invention consists, essentially, of an attachment having a gas-passage in which there is located a valve controlled by a spring and a diaphragm, said 20 diaphragm forming one of the walls of an air-chamber arranged in close proximity to the burner-tip, all as will be hereinafter more fully described, and specifically pointed out in the claims.

Reference is to be had to the accompanying drawings, forming a part of this specification, in which similar figures and letters of reference indicate corresponding parts in all the views.

30 Figure 1 is a central sectional elevation of our safety-burner, the view being taken on line $x-x$ of Fig. 3. Fig. 2 is a face view of the burner. Fig. 3 is a rear view thereof. Fig. 4 is a cross-sectional view on line $y-y$ of Fig. 35 1, and Fig. 5 is a face view of the valve.

In the drawings, 10 represents the body or barrel of a burner, at one end of which there is secured the ordinary tip 11, while the other end of the body is arranged for connection 40 with the nipple of a gas-fixture. A partition, 12, divides the body 10 into two chambers or compartments, A B, communication between the said chambers or compartments being at times established by means of a passage 45 formed in an arm, 14, the passage (as arranged in the drawings) being made up of a lower passage or bore, a , a valve-chamber, 15, a chamber, 16, and an upper passage or bore, b .

The chamber 16 is formed by a disk, 17, and 50 a diaphragm, 18, said diaphragm being secured to the disk by a cap, 19, that is internally

threaded to engage a thread cut upon the peripheral edge of the disk, whereby an air-tight chamber, C, is formed between the outer face of the diaphragm and the inner surface 55 of the cap.

Within the chamber 15 there is arranged a valve, 20, that is normally held to its seat by a spring, 21, coiled about the valve-stem, one end of the spring abutting against the valve-head and the other against a plug, 22, arranged as shown. As before stated, the valve 20 is normally seated, and consequently all communication between the bore or passage a and the bore or passage b is normally 65 closed; but if the air within the chamber C be heated it will become rarefied and the diaphragm 18 will be moved to about the position in which it is shown in Fig. 1, thus opening a passage through the disk 17 and 70 establishing communication between the gas-fixture and the chamber B of the barrel 10, the burning of the gas at the tip of the burner maintaining sufficient heat within the chamber C to hold the diaphragm in the position shown; but if the gas should go out or be blown out the air within the chamber C would contract, and as the air so contracted the diaphragm 18 would move to the position indicated by dotted lines in Fig. 1, thus leaving the spring 21 free to act to force the valve 20 to its seat, thus cutting off all communication between the gas-supply and the burner-tip. 75

To light the gas, the plug of the fixture is 80 turned and a match or other proper heat-producing lighter is held in close proximity to the cap 19. Then as the air within the chamber C becomes rarefied the valve 20 will be forced from its seat, thus establishing a 85 passage for the gas from the fixture to the burner-tip.

Although we have described a specific form of safety-burner, we desire it to be distinctly understood that any burner provided with a 90 gas-passage in which there is arranged a valve that is controlled by the action of a confined volume of air would be within the spirit of our invention.

In practice the diaphragm 18 would be 95 made of any proper material, thin-sheet German silver being preferred, and although any

good conducting material could be employed in the construction of the cap 19, we prefer to employ copper.

Having thus described our invention, we claim as new and desire to secure by Letters Patent—

1. The combination, with a burner-body divided into upper and lower chambers or compartments, of an arm extending upward from the side of the burner-body and formed with gas-passages which connect the burner-body chambers, a cap and diaphragm carried by the arm and forming an air-tight chamber, a valve mounted to control the gas-passages and arranged to bear against the diaphragm, and a spring arranged in connection with the valve, substantially as described.

2. The combination, with a burner-body divided into chambers A and B, of an arm formed with passages *a* and *b* and a valve-chamber, a valve mounted within the chamber, a diaphragm arranged in advance of the valve, and a cap connected to the arm in advance of the diaphragm and forming therewith an air-chamber located in close proximity to the burner, substantially as described.
